US00D946472S

(12) **United States Design Patent** (10) **Patent No.:** **US D946,472 S**
(45) **Date of Patent:** **** Mar. 22, 2022**

(54) **FENDER WITH INTEGRATED LOCK**

(71) Applicant: **Lyft, Inc.**, San Francisco, CA (US)

(72) Inventors: **Ethan Duncan Eyler**, San Francisco, CA (US); **Alejandro Salvador Garcia**, San Francisco, CA (US); **Peter Rex Luedtke**, New York City, NY (US); **Jesse Jones McMillin**, San Francisco, CA (US); **Rasmus Breitholtz**, San Francisco, CA (US); **Stijn Jagers**, San Francisco, CA (US); **Sang Ik Lee**, San Francisco, CA (US); **Zachary London**, San Francisco, CA (US); **Victoria Slaker**, San Francisco, CA (US)

(73) Assignee: **Lyft, Inc.**, San Francisco, CA (US)

(**) Term: **15 Years**

(21) Appl. No.: **29/747,646**

(22) Filed: **Aug. 24, 2020**

Related U.S. Application Data

(63) Continuation of application No. 29/679,801, filed on Feb. 10, 2019, now Pat. No. Des. 894,050.

(57) **CLAIM**

The ornamental design for a fender with integrated lock, as shown and described.

DESCRIPTION

FIG. 1 is a perspective view of a fender with an integrated lock;

FIG. 2 is a right view thereof;

FIG. 3 is a left view thereof;

FIG. 4 is a rear view thereof;

FIG. 5 is a top view thereof;

FIG. 6 is a bottom view thereof;

FIG. 7 is a front view thereof; and,

FIG. 8 is a perspective view of a fender with an integrated lock and environmental structure.

The broken lines are included for the purpose of showing environmental portions of the fender with an integrated lock and form not part of the claimed design.

1 Claim, 8 Drawing Sheets
